UNITED STATES PATENT OFFICE.

EDWARD E. GREENE, OF NEW YORK, N. Y., ASSIGNOR TO HIMSELF AND GAMALIEL R. CHRISTIE, OF SAME PLACE.

COMBINED WALKING-STICK AND UMBRELLA.

SPECIFICATION forming part of Letters Patent No. 572,983, dated December 15, 1896.

Application filed January 13, 1896. Serial No. 575,208. (No model.)

To all whom it may concern:

Be it known that I, EDWARD E. GREENE, a citizen of the United States, and a resident of New York city, county of New York, and 5 State of New York, have invented certain new and useful Improvements in a Combined Walking-Stick and Umbrella, of which the following is a specification, reference being had to the accompanying drawings, forming 10 a part thereof, in which similar letters and numerals of reference indicate corresponding parts.

This invention relates to improvements in combined walking-sticks and umbrellas, and 15 has for its object to provide an article of this character which will be durable, inexpensive, and operative.

The device will comprise few and simple parts, which will be assembled in such a manner as to admit of very rapid adjustment.

The invention will be hereinafter fully described, and specifically set forth in the annexed claim.

In the accompanying drawings, Figure 1 is 25 a vertical elevation of my improved walking-stick and umbrella. Fig. 2 is a sectional elevation thereof, and Fig. 3 is a folded view of the telescopic casing forming part of my device.

30 In the practice of my invention I provide an umbrella A with a contracted stick or rod a and an enlarged handle a'.

To the lower end of the handle a' is attached a ring b. Said ring is provided with an annular groove b', which engages with a flange c' of a collar C. This said collar is provided with an interior thread c', which engages with a threaded flange d on the upper section 1 of the telescopic casing B. This said casing comprises a series of tubular and conical sections 35 1, 2, 3, and 4, the lower section thereof being supplied with a ferrule e, which should be composed of some hard and durable metal.

The sections themselves are preferably composed of aluminium; but they may be made 45 of celluloid, gutta-percha, or other desirable material, and in practice they should be painted or stained to a color exactly matching the handle of the umbrella, whereby the 50 general appearance of a cane or walking-stick is maintained when the casing is extended

and secured to the umbrella, as shown in Fig. 1.

The handle of the umbrella is further provided at its outer end with a screw-cap f, 55 which can be removed and attached to the threaded flange d of the section 1 of the telescopic casing when said casing is folded, as clearly illustrated in Fig. 3.

The cap f and the collar C should be made 60 of some valuable metal—such as silver, for instance—and they may be ornamented by any suitable design to preserve the appearance of a cane when the device is being carried as such.

When it is desired to use the umbrella, it is simply necessary to revolve the collar C until it is out of engagement with the flange d of the casing, when the several sections of said casing may be readily folded, as illustrated in Fig. 3, and when the cap f is adjusted it will be seen that the sections cannot become permanently separated from each other, while at the same time they form a small and compact package adapted to be 75 easily carried in the pocket.

To insure that the umbrella will not rattle or move within its casing, the section 4 of the said casing is provided with a deep socket e', which is adapted to tightly hold the lower 80 end of the stick or rod a of the umbrella. When the casing is folded, a slight pull will readily detach said section from the stick.

The operation of attaching the casing to the handle is performed in a manner similar to 85 that of detaching the same, with the exception that the collar C must be revolved in an opposite direction.

I do not claim the construction of a combined walking-stick and umbrella broadly, as I am 90 aware that the same has been patented and used; but I have contrived a novel construction and arrangement of parts which are better adapted for the purpose and simpler than any known to me.

Having thus described my invention, what 95 I claim as new, and desire to secure by Letters Patent, is—

As a new article of manufacture, a combined walking-stick and umbrella consisting 100 of umbrella A, having a stick a, handle a', ring b in lower end of handle a', said ring

having annular grooves b' engaging with flange c' of collar C, said collar having an interior thread c^2 engaging with flange d in upper section of casing B, having a ferrule e ,
5 a screw-cap f attached to said handle and a socket e' in the lower end of the casing B, all operating substantially as shown and described.

In testimony that I claim the foregoing as my invention I have signed my name, in presence of two witnesses, this 7th day of January, 1896.

EDWARD E. GREENE.
